Application May 22, 1935, Serial No. 22,812

4 Claims. (Cl. 217—12)

This invention relates to knock-down receptacles or crates, and more particularly to means for assembling and securing the separate panels or sections of the completed receptacle or crate.

5 Numerous plates, fasteners or clips have been used in assembling knock-down receptacles or crates, and heretofore it has been necessary to perform secondary or auxiliary operations after assembly to insure a perfectly finished receptacle. Such auxiliary operations may include hammering, punching, crimping, pressing, etc.

It is an object of this invention to eliminate auxiliary and secondary operations in assembling knock-down receptacles or crates by providing 10 a securing or fastening means that is practicable and complete in one assembling operation.

Another object is to provide a resilient gripping clip or fastening means that is simple in construction, yet thoroughly suitable for a ready and quick assembly of the separate panels or 15 sections of a knock-down receptacle or crate.

Another object is to provide a clip of such a shape and strength as to insure constant gripping of the separate panels or sections after assembly. 20 Other objects and advantages will be apparent from the following description of the drawing in which:

Figure 1 is a plan view of a receptacle or crate in assembled form, being shown with its cover 25 removed, and embodying the improved securing element;

Figure 2 is a side sectional view of the same taken along the line 2—2 of Figure 1, and showing the cover in place;

30 Figure 3 is a fragmentary view of the bottom and end and side panels in separate relation;

Figure 4 is an oblique perspective detail view of one of the clips used in assembly;

Figure 5 is a view similar to Figure 4, showing 35 a modified form of clip; and,

Figure 6 is a view similar to Figure 3, employing the modified clip in position.

In the drawing a receptacle is shown generally at 40, having a bottom panel or section 11, and adjacent end panels or sections 12, and side panels or sections 13. The bottom panel 11 is reinforced by strips 14 on its under side. A top or cover 14 is included in Figure 2.

45 At each end of the bottom panel 11 and on its upper surface, as best shown in Figures 2 and 3 are securing means for securing the end panels 12 thereto, said securing means being in the form of a pair of spaced members such as the inner and outer strips or battens 15 and 15', and

resilient gripping means such as the securing elements or clips 16. As best shown in Figure 1, the side panels 13 are each provided at either end with a similar securing means comprising inner and outer strips 17 and 17' and the clips 16. The strips 15 and 15' and 17 and 17' preferably extend across the entire width of the bottom and side panels 11 and 13 respectively to afford reenforcement besides another function to appear later.

As shown in Figures 1, 2, 3, and 4 the securing means or clip 16 is formed as an angular metal member with a base portion 18 having at its outer end and substantially at right angles thereto, a bent up portion or lip 19, and at its inner end 5 and substantially parallel to the lip 19, a bent up extension or leg 20. The bent up leg 20 is further bent over at its upper end to form an acute angular projection or gripping portion 21.

As best shown in Figures 2 and 3 the clips 16 are secured to the bottom panel by the outer strips 15' across the base portions 18 and between the bent up lip 19 and the leg 20, leaving sufficient space between the inner edge of the strip 15' and the leg 20 to allow insertion of the end panels 12 therebetween and past the angular projections or gripping portions 21. The clips 16 are preferably made of spring steel of sufficient strength and resiliency to insure a constant grip as the angular projections 21 engage the end panels 12. The clips 16 are similarly secured to the side panels 13 by the outer strips 17', also allowing for the insertion of the end panels 12.

The securing element or clip 22 shown in Figures 5 and 6 is a modified construction of the clip 16 shown in Figure 4, having the base portion 18, and the bent up portion and extension or lip 19 and leg 20. In the clip 22, the bent up extension or leg 20 is further extended and rolled over at 20', being further bent out to form the acute 40 angular projection or gripping portion 21'. This rounded portion 20' increases the spring or resiliency of the angular projection 21' affording a better grip upon engaging an inserted panel.

The separate panels or sections of knock-down receptacles or crates of the class described are usually cut and manufactured at a mill, and are completed in every respect but assembly, as is well known to those skilled in the art. A number of panels sufficient to assemble one receptacle or crate are included together, and the receptacle in that condition is termed knocked-down; that is, enough sections to be readily assembled. The securing means that is the subject of this invention facilitates ready assembly when the re-

ceptacle or crate is to be utilized in packing or shipping.

The procedure usually followed at the mill or place of manufacture consists of forming the 5 bottom panels or sections with the reinforcing strips 11', the spaced members or battens 15 and 15', and the securing elements or clips 16 or 22 in place. The side panels or sections are similarly completed with the spaced members 17 and 17' and the securing elements 16 or 22 in place. The end panels or sections 12 and the top or cover 14 are formed with sufficient reenforcement and are included with the other panels and sections as one unit for assembling one receptacle or 15 crate.

When the receptacle or crate is to be used for packing or shipping the separate panels or sections are assembled. The opposite edges of the end panels or sections are inserted from above 20 between the strips 17 and 17' and the clips 16 or 22 on the adjacent side panels or sections in such a manner as will engage the angular projections 21 or 21' with the inner surfaces of the end panels 12.

25 The resilient construction of the clips 16 or 22 causes the angular projections 21 or 21' to grip or to bite into the end panels 12, holding the end panels securely adjacent the side panels 13 and between corresponding strips or battens 17 and 30 17'. It is obvious that an attempt to pull out or loosen the end panels 12 from the side panels 13 only results in the acute angular portions 21 or 21' digging more deeply into and gripping more securely the end panels 12. After each end panel 35 12 is secured to each of the side panels 13, forming a rectilinear construction without top or bottom, the unit of end and side panels or sections is placed on the bottom panel 11 in such a manner as will cause the insertion of the bottom edges 40 of each end panel 12 between each pair of strips or battens 15 and 15' on the bottom panel or section and in gripping engagement with the angular projections 21 or 21'.

Thus an entire receptacle, with the exception 45 of a cover, is completed or assembled by the simple expedient of inserting the ends of adjacent panels into securing means formed on separate panels, thus largely eliminating further operations such as hammering, crimping, etc.

50 Similar to the assembly of the end panels 12 and the side panels 13, the addition of the bottom panel 11 provides for the same constant security against loosening or pulling apart because of the increased grip or biting of the angular projections 21 or 21'.

55 After the receptacle has been filled the cover 14 is nailed or wired in place, this operation requiring the only secondary operation in the entire assembly.

60 The cover 14 is nailed or wired in place to the end panels 12 and the side panels 13 merely to effect easy removal of the cover without destroying the receptacle. Similar securing means as are employed in securing together the side, end, 65 and bottom panels or sections, may be employed in securing the top or cover to the receptacle.

It will be apparent that only the preferred embodiments of the invention have been shown, and various clips of the type disclosed may be employed without departing from the scope of the invention.

5

What is claimed is:

1. The combination with a container having a pair of side panels, a pair of adjacent end panels and an adjacent bottom panel, of securing means on each of said side panels, securing means on 10 said adjacent bottom panel, said securing means comprising clip holding members and resilient gripping elements cooperating with said holding members, and penetrating extensions on said elements bent in the direction of introduction of 15 the end panels, whereby each of said end panels is secured to each of said adjacent side panels and to said adjacent bottom panels by the gripping action of said resilient gripping elements upon insertion, in a direction substantially at 20 right angles to an adjacent panel, of each of said end panels between said securing means on said adjacent side panels and between said securing means on said adjacent bottom panel.

2. A resilient gripping element for attaching 25 adjacent panels at right angles, said gripping element consisting of spring metal and comprising a base portion adapted to be secured to one of said panels, a bent extension at one end of said base portion and substantially at right angles 30 thereto, and an acute angular projection at the free end of said bent extension, said angular projection extending downwardly toward the free end of the first leg being thereby inclined in the direction of introduction of an adjacent panel 35 for gripping engagement therewith to prevent withdrawal of the assembled panels.

3. A resilient gripping element for securing adjacent panels at right angles, said gripping element consisting of an angular member of spring 40 metal one leg of which is adapted to be secured to one of said panels with the second leg upright, the second leg being bent at its free end to form an acute angular projection, said angular projection extending downwardly toward the free 45 end of the first leg being thereby inclined in the direction of and extending into the path of introduction of an adjacent panel for gripping engagement therewith to prevent separation of the assembled panels.

50 4. A resilient gripping element for securing adjacent panels at right angles, said gripping element consisting of an angular member of spring metal one leg of which is adapted to be secured to one of said panels with the second leg upright, 55 the second leg being formed with a rolled portion, said rolled portion being further bent away from said second leg to form an angular projection, said angular projection extending downwardly toward the free end of the first leg being thereby 60 inclined in the direction of and extending into the path of introduction of an adjacent panel for gripping engagement therewith to prevent separation of the assembled panels.
